No. 852,889.

PATENTED MAY 7, 1907.

R. MIEHLE.
PISTON FOR AIR COMPRESSORS.
APPLICATION FILED JULY 24, 1905.

UNITED STATES PATENT OFFICE.

ROBERT MIEHLE, OF CHICAGO, ILLINOIS.

PISTON FOR AIR-COMPRESSORS.

No. 852,889.

Specification of Letters Patent.

Patented May 7, 1907.

Application filed July 24, 1905. Serial No. 270,917.

To all whom it may concern:

Be it known that I, ROBERT MIEHLE, a citizen of the United States, residing at Chicago, in the county of Cook and State of Illinois, have invented a new and useful Improvement in Pistons for Air-Compressors, &c., of which the following is a specification.

This invention relates to pistons for air compressors, air cushioning devices for printing press beds, lathe beds, dash-pots and pumps, and more particularly to that type of piston depending upon a "cup leather" as its packing.

The improvements are addressed to the means for expanding the packing or cup leather, and the invention has for its object to provide a means for this purpose which shall be simple and efficient, and in which liberal provision is made for ingress of the air to the cup leather around the edges of the expander.

The invention consists in the features of novelty by which these objects and certain other objects which will hereinafter appear are accomplished, all as fully described with reference to the accompanying drawings, and more particularly pointed out in the claims.

In the said drawings,—Figure 1 is a longitudinal sectional view of a piston embodying this invention; Fig. 2 is a face-view thereof, looking from the right in Fig. 1; Fig. 3 is a detail view of the strip or blank of which the spreader is composed; Fig. 4 is an enlarged detail view of one end thereof; and Fig. 5 is a cross-section thereof, showing the tongues of the spreader bent to their final form.

1 is the piston head, which may be provided with a hub 2 for the attachment of the piston rod, not shown, or any other suitable connection, the head being of the usual or any appropriate form, with a peripheral flange 3 near one end thereof, which constitutes a seat or shoulder against which is arranged the inner edge of the aforesaid spreader 4. This spreader is composed preferably of a single strip of sheet steel, or any other suitable elastic substance possessing the requisite strength, which is provided throughout its entire length with long and

short tongues 5, 6, 7, extending transversely of the strip, which is lapped around the head 1 with its edge against the flange or seat 3, as before mentioned. These tongues 5, 6, 7, may be produced by slitting the strip transversely, and the strip being composed of steel or elastic material the tongues will constitute

individual springs. The shortest of these tongues, which is shown at 6, have their outer ends bent outwardly at substantially right angles to their body portions to form flanges or lugs 8, which engage with the outer edge of a ring 9, composed of leather or any other suitable flexible material, arranged on the head 1 around the band 4 at a position between the flange 3 and thes flugs 8 of the tongues 6, where by the ring 9 will be held in place. These short tongues 6 may be employed throughout the length of the band 4 at suitable intervals apart, as may be required for retaining the ring 9 in place. In the exemplification of the invention shown in the drawings they occur between every alternate pair of the tongues 5, which are longer than the tongues 6, and have their outer ends bent first inwardly as shown at 5^a, with respect to the center of the head 1, and then outwardly as shown at 5^b, to produce beveled or inclined extremities against which bears an expander 10. This expander is preferably in the form of a ring having a beveled periphery or side 11 bearing against the inclined or beveled ends 5^b of the tongues 5, and serving, when the expander is moved toward the tongues 5, to force the outer ends of the tongues outwardly in a radial direction with respect to the head 1 and thereby also crowding the band or ring 9 outwardly against the packing of the piston, which as before mentioned, is constituted by a cup leather 12 of the usual or any suitable form, arranged over and embracing the band 9, and having its bottom portion secured to the back of the head 1 in any suitable way, as by means of a clamping ring 13, which is held in place by the same bolts 14 which secure and adjust the expander 10, the expander 10 being arranged inwardly with respect to the lip 15 of the cup leather and outwardly with respect to the edge of the ring 9 and the head 1, so as to leave a liberal passage around the expander for the ingress of the air to the cup leather, thereby avoiding the possibility of the space between the lip of the cup leather and the periphery of the expander becoming clogged with grease or dirt and rendering the device inoperative.

The longest of the tongues, or the tongues 7, which occur at suitable intervals throughout the length of the band 4, and preferably between every alternate pair of the tongues 5, are bent inwardly at an angle to their body portions and radially with respect to the center of the head, but at an oblique angle to the

- axis of the head, as shown at 7^a, and serve as a bearing for the expander 10, and at the same time as a means for preventing the spreader constituted by the band 4 and its various tongues 5, from, by any possibility, slipping out of its seat on the head. These angular bends 7^a of the longest tongues 7 also, by virtue of their elasticity, constitute a means of holding the expander 10 snugly against the nuts 16 of the bolts 14, and thereby not only preventing undue play of the expander, but producing sufficient pressure against the nuts to prevent them from working loose.
- 15 With a device thus constructed it will be seen that the inward movement of the expander 10 causes the spreader tongues 5 to move outwardly with a rotary direction of motion, taking for its center the point of conjunction between the tongue and the body of the band or strip 4, and by thus moving outwardly they expand the leather or flexible ring 9 uniformly throughout its circumference, but at an angle to the axis of the head,
- 20 so that the cup leather 12 will be pushed outwardly with uniformity and with its greatest expansion at the edge or lip 15. It will also be seen that the spreader tongues 5, being turned inwardly by the bends 5^a and thence outwardly by the bends 5^b, and the surface of the expander being beveled where it engages with the corresponding beveled extremities 5^b of the tongues, a great range of expansion is provided for.
- 25 30 35 Having thus described my invention, what I claim as new therein, and desire to secure by Letters Patent, is:
1. In a device for the purpose described, the combination with a piston head, a packing embracing the same, and an expander movable toward the head, of spreaders interposed at intervals between the head and packing and comprising elastic spreading tongues, and means whereby the expander 40 engages and spreads the spreaders toward the packing.
  2. In a device for the purpose described, the combination with a piston head and a packing embracing the same, of a beveled expander movable toward the head, and spreaders embodying elastic tongues interposed between the head and packing and arranged to be engaged by the bevel of said expander.
  3. In a device for the purpose described, the combination with a piston head, a packing embracing the same, and an expander movable toward said head, of spreaders interposed between the packing and head and having beveled or flaring ends engaged by the expander said spreaders comprising,

elastic tongues against which the expander engages.

4. In a device for the purpose described, the combination with a piston head, a packing embracing the same, and an expander movable toward said head, of a spreader for the packing interposed between the packing and the head and comprising elastic tongues against which the expander abuts, and elastic spreading tongues between which the expander engages for expanding the packing.

5. In a device for the purpose described, the combination with a piston head, a packing embracing the same and an expander movable toward the head, of an elastic band encircling the head under the packing and comprising outwardly extending elastic tongues, some of said tongues being bent inwardly and serving as a bearing for the expander, and others of said tongues being arranged to partially embrace the expander, whereby the inward movement of the expander will spread said lateral tongues toward the packing.

6. In a device for the purpose described, the combination with a piston head, a packing embracing the same, and an expander movable toward said head, of an elastic band embracing the head under the packing and comprising outwardly extending elastic tongues, which have their outer extremities bent first inwardly with respect to the center of the head, and then outwardly or flared and engaging with the periphery of the expander.

7. In a device for the purpose described, the combination with a piston head, and a packing engaging the same, of a beveled expander movable toward the head, a plurality of elastic spreader tongues arranged between the head and the packing and having their outer extremities flared outwardly and engaging against the bevel of said expander.

8. In a device for the purpose described, the combination with a piston head, a cup leather surrounding the head, a ring interposed between the cup leather and the head, and an expander movable toward the head, of an elastic band embracing the head under the said ring and comprising radially extending lugs engaging over the edge of said ring for holding the ring in place, and longitudinally extending tongues between which said expander engages for forcing the ring outwardly against the cup leather.

In witness whereof, I have hereunto set my hand this 22nd day of July, 1905, in the presence of the subscribing witnesses.

ROBERT MIEHLE.
